(57) CLAIM

The ornamental design for a weight cart, as shown and described.

DESCRIPTION

FIG. 1 is a perspective view of a weight cart showing our new design;

FIG. 2 is another perspective view of the design of FIG. 1; FIG. 3 is a front elevational view of the design of FIG. 1; FIG. 4 is a rear elevational view of the design of FIG. 1; FIG. 5 is a left side elevational view of the design of FIG. 1;

FIG. 6 is a right side elevational view of the design of FIG. 1;

FIG. 7 is a top plan view of the design of FIG. 1; and, FIG. 8 is a bottom plan view of the design of FIG. 1.

The broken line showings are included for the purpose of illustrating environment and form no part of the claimed design for a weight cart.
